US00D939798S

(12) **United States Design Patent** (10) **Patent No.:** **US D939,798 S**
(45) **Date of Patent:** **** Dec. 28, 2021**

(54) **CLEANER**

(71) Applicant: **Samsung Electronics Co., Ltd.**, Suwon-si (KR)

(72) Inventors: **Sanghoon Yoon**, Suwon-si (KR); **Jinsun Park**, Suwon-si (KR); **Kangkyung Lee**, Suwon-si (KR); **Hwandard Lee**, Suwon-si (KR)

(73) Assignee: **SAMSUNG ELECTRONICS CO., LTD.**, Gyeonggi-Do (KR)

(**) Term: **15 Years**

(21) Appl. No.: **29/726,311**

(22) Filed: **Mar. 2, 2020**

(30) **Foreign Application Priority Data**

Sep. 3, 2019 (KR) 30-2019-0042466

(51) **LOC (13) Cl.** **15-05**

(52) **U.S. Cl.**

USPC **D32/22**

(57) **CLAIM**

The ornamental design for a cleaner, as shown and described.

DESCRIPTION

FIG. 1 is a front perspective view of a cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines depict portions of the cleaner and environmental structure that form no part of the claimed design.

1 Claim, 7 Drawing Sheets
